UNITED STATES PATENT OFFICE.

EDWARD C. HOLMES, OF NORWOOD, OHIO.

BUMPING-POST FOR RAILROADS.

1,170,639.

Specification of Letters Patent.

Patented Feb. 8, 1916.

Application filed June 17, 1914. Serial No. 845,526.

To all whom it may concern:

Be it known that I, EDWARD C. HOLMES, a citizen of the United States, and a resident of the city of Norwood, in the county of 5 Hamilton and State of Ohio, have invented certain new and useful Improvements in Bumping-Posts for Railroads, of which the following is a full, clear, and exact description, reference being had to the accompanying 10 drawings, forming part of this specification.

My invention relates to bumping posts for use on railroads to stop the rolling stock from running off the track terminals, and 15 the object is to furnish a substantial and durable post that can be easily manufactured and which shall be adapted to effectively withstand the shock of heavy blows.

The invention consists of that certain 20 novel construction and arrangement of parts to be hereinafter particularly pointed out and claimed whereby the body of the post may be constructed of concrete adapted to withstand great crushing strains and in 25 which the force of the blow delivered longitudinally to the receiving head may be translated largely in a downward or vertical blow by reason of the pivotal construction of the head.

30 In the drawings, Figure 1 is a side elevation of my improved construction with part of the receiving head in section. Fig. 2 is a top plan view of the same. Fig. 3 is a front elevation. Fig. 4 is a detailed trans- 35 verse section of the track support in front of the bumper attachment. Fig. 5 is a perspective view of the supporting plate for the receiving head. Fig. 6 is a perspective view of the rail supporting plate. Fig. 7 40 is a side and end elevation of one of the pivot pins for the rock arms.

The bumping post proper is a solid and substantial standard 1, preferably constructed of concrete and preferably in the 45 shape of a truncated pyramid with rounded edges. This post is provided with a broad substantial base portion 2, which is seated in a socket 3 in a concrete bed 4. The post is 50 yieldingly supported in the socket by a series of substantial coiled springs 5, 6, which fill the base of the socket. As an effective construction of springs, I prefer to provide the smaller spring 6 within the coils of the larger springs 5.

55 Bolted with bolts 7, 7, or otherwise per-

manently and effectively secured on top of the truncated upper end of the standard 1, is a bearing plate 8, with vertical side flanges 9, 9, and mounted to rock between these side flanges is the substantial metal 60 casting 10, forming the receiving head for the bumper. This head is provided with an angular or curved rocking surface 11 and with a socket 12 in which is seated the striking plate 13, with the socket portion preferably cylindrical in shape and formed with steps or shoulders 14 on its inner end. Interposed between the striking plate and the base of the socket are a series of coiled springs 15, 16 and 17, one within the other, 70 seated on the stepped portion of the striking plate, with the larger and heavier springs on the outside.

Securely bolted to the sides of the head 10 by the bolts 18 are the rocker arms 19, 75 19. These arms extend downwardly and flare outwardly to the width of the track rails 20 in front of the bumping post where they are pivotally mounted by the substantial pivot pins 21 on the upwardly extending lugs 22, 22 of the securing plates 23. These plates have depending flanges 24 to engage the web of the rail where they are 80 securely bolted by the bolts 25. As these bolts are subjected to great strain when the bumper post is struck, they are provided with the ears 26 to receive the ends of the U-bolts or straps 27, which pass down on each side of the rail alongside of the sleeper 28 and around an I-beam 29 underneath 90 the sleeper. These I-beams extend some distance along underneath and parallel to the track, and the track rails are further strapped to these I-beams by the U-bolts or straps 30, which engage the rail flanged 95 plates 31, which are slipped over the rail from the end to engage the flange of each side. In this way the receiving head of the bumper is securely coupled to the track construction.

100 When the bumper post is struck by the rolling stock, the striking plate 13 receives the blow yieldingly by reason of the coiled springs, and the receiving head 10 is rocked to direct the force of the blow downwardly 105 upon the concrete standard. The rocker arms 19 also rock on their pivots 21 to properly allow for this change of direction of the blow.

Having thus described my invention, what 110

I claim as new and desire to secure by Letters Patent, is:—

1. In a device of the character specified, a concrete standard, a receiving head slid-
5 ingly mounted thereon, rocker arms secured to the receiving head, with pivotal connec-
tions for the arms with the track structure
whereby the force of a horizontal striking
blow may be converted into a blow at right
10 angles thereto upon the concrete standard.
2. In a device of the character specified,
a concrete standard, with a yielding verti-
cal support therefor, a receiving head slid-
15 ingly mounted thereon, rocker arms secured
to the receiving head, with pivotal connec-
tions for the rocker arms with the track
structure whereby the force of a horizontal
striking blow may be converted into a blow
20 at right angles thereto upon the concrete
standard.
3. In a device of the character specified,
a concrete standard, with a yielding vertical
support therefor, a receiving head slid-
25 ingly mounted thereon, rocker arms secured to the
receiving head, with pivotal connections for
the rocker arms with the track structure,
the receiving head provided with a hori-
zontal socket and a striking plate mounted in
30 the socket in the receiving head, with
springs to serve as a yielding cushion.
4. In a device of the character specified,
a vertical standard, with a bearing plate on
top thereof, the plate provided with side
35 flanges, a receiving head mounted to slide
and to rock between said flanges, and rocker
arms secured to the receiving head and piv-
otal connections with the track structure.
5. In a device of the character specified,

a vertical standard, with yielding cushion
for the standard, and a bearing plate on top
40 of the standard, the plate provided with
side flanges, a receiving head mounted to
slide and to rock between said flanges, and
rocker arms secured to the receiving head
45 and pivotal connections with the track
structure.

6. In a device of the character specified,
a vertical standard, a receiving head slid-
ingly mounted thereon, a track structure
comprising rails and sleepers, with I-
50 beams underneath the sleepers parallel with
the track rails, securing plates bolted to the
track rails, and U-straps to secure the se-
curing plates to the I-beams, with rocker
55 arms secured at one end to the receiving
head and pivotal connection for said arms
at the other end to the securing plates.

7. In a device of the character specified,
a standard, a receiving head slid-
ingly mounted thereon, rocker arms secured to the
receiving head, with pivotal connections for
the rocker arms with the track structure,
the receiving head provided with a hori-
60 zontal socket, and a striking plate mounted in
the socket in the receiving head, the striking
plate provided with a stepped portion in
the rear, and a series of coiled springs
65 graded in size seated between the stepped
portion and the base of the socket to serve
as a yielding cushion with the smaller
springs inside the larger.

EDWARD C. HOLMES.
